UNITED STATES PATENT OFFICE.

ROBERT HAUSDORF, OF BOCHUM, GERMANY.

APPARATUS FOR STORAGE AND DELIVERY OF INFLAMMABLE LIQUIDS.

977,188.

Specification of Letters Patent. Patented Nov. 29, 1910.

Application filed May 3, 1910. Serial No. 559,220.

To all whom it may concern:

Be it known that I, ROBERT HAUSDORF, of Bochum, Kanalstrasse 49, Germany, have invented a certain new and useful Apparatus for the Storage and Delivery of Inflammable Liquids, of which the following is a specification:

In apparatus for the storage and delivery of inflammable liquids, of the class wherein an inert gas is introduced without pressure, or nearly without pressure, into the evacuated space of the storage receptacle, great risk is involved owing to the fact that if the receptacle or the conduit supplying the inert gas becomes leaky the apparatus can continue to work, but then sucks in air. As regards leakage in the conduit, the danger can be averted by means of suitable pipe-fracture safety devices, but the danger remains in regard to the filling pipes of the storage receptacle. If the automatic valves pushed back by the unions of the pipes connected to the supply-barrel are not tight, or if connection to the air is made intentionally (either with malicious intent or in order to allow of continued working after disturbance has occurred), air can enter the apparatus without producing any noticeable effect on the function thereof.

The present invention wholly obviates this disadvantage by providing in the filling conduit a valve positively connected to a valve in a conduit which must be opened for the purpose of delivery of liquid, these valves being so arranged that when either of them is closed the other is open. It follows that during the delivery of liquid the filling conduit is closed, and no air-suction is possible, and that during the filling of the storage receptacle there can be no delivery and therefore no evacuation enabling air to enter. The slight attendant restriction, that simultaneous delivery and filling are not possible, is wholly outweighed by the increased safety obtained.

The valves may be manually operated, but preferably the action is automatic in so far that the coupled valves tend to automatically assume the position in which the delivery pipe is open, and are moved from this position by the placing of a supply barrel in position for replenishing the store.

A construction embodying the device described is shown in the annexed drawings, in which—

Figure 1 is a vertical section of the com-

plete installation, and Fig. 2 a section of the coupled valves referred to.

In the drawings, *a* represents the subterranean main storage receptacle, which communicates with an auxiliary receptacle *c* by means of an anti-return valve *b*. From one compartment of the receptacle *c* a rising-pipe *d* for the inflammable liquid leads to a three-way cock *e*, to which is joined a pipe *f* for supplying gas under pressure to a pipe *g* leading to the other compartment of the receptacle *c*. The two compartments of the latter communicate with each other at the bottom. Inflammable liquid flows from the main receptacle *a* to the receptacle *c* when pipe *g* is placed in communication with a gas-discharge pipe *v*. The space evacuated by the liquid in the receptacle *a* is filled with carbon dioxid flowing at low pressure from the flash *h* through pipe *i*. By turning the cock *e* to open pipe *d* and connect pipe *f* to pipe *g*, the fluid under pressure is caused to force liquid from receptacle *c* through the pipe *d*, the return of the liquid to receptacle *a* being prevented by valve *b*. The supply-pipe *k* terminating in the receptacle *a*, near the bottom of the same, is connected by a flexible pipe *l* to the bung-hole of the portable barrel *m*. The pipe *n* joined to the top of the receptacle *a* is connected by a flexible pipe *o* to a pipe *p* passing through the bung-hole and terminating near the top of the barrel. The pipes *k* and *n* are both joined to a rotary valve *q* by means of which these two pipes can be simultaneously opened and closed. The valve *q* is coupled with a rotary valve *r* in the pressure pipe *g*, the passages of the two valves being so arranged that pipe *g* is open when pipes *k* and *n* are closed, and vice versa. This is the arrangement of coupled valves described in the opening part of the specification. It is not essential that the pipe *k* is joined to the valve *g*, inasmuch as only the pipe *n* could under ordinary conditions admit air to the receptacle *a*, but for additional safety, and in view of the simplicity of the device it is advisable to valve both the pipes *k* and *n*.

A spring *s* acts on the valves *q* and *r* through a rod *u*, so that normally the pipes *k* and *n* are closed, but when the pipes *o* and *l* have been joined to the barrel and the latter is rotated on the support *t* into the position shown in Fig. 1, the union connecting the pipes *l* and *o* to the barrel moves the rod *u* against the action of the spring, so that

valve *q* is opened and valve *r* closed. The rod *u* may be locked to prevent unauthorized actuation thereof, but even malicious actuation of the rod would only prevent delivery of the liquid from receptacle *a*, and would not involve danger to the apparatus.

What I claim as my invention and desire to secure by Letters Patent of the United States is:—

- 10 1. Apparatus for storage and delivery of inflammable liquid, comprising a storage receptacle, means for introducing an inert gas into the space evacuated by the liquid in the storage receptacle, a liquid supply barrel, a 15 liquid supply conduit connecting said barrel with the storage receptacle, an auxiliary receptacle adapted to communicate with the storage receptacle, a pressure conduit communicating with the auxiliary receptacle, a 20 valve in each of said conduits, and means for so connecting said valves that while one valve is opened the other valve is closed.

2. Apparatus for storage and delivery of inflammable liquid, comprising a storage receptacle, means for introducing an inert gas 25 into the space evacuated by the liquid in the storage receptacle, a liquid supply barrel, a liquid supply conduit connecting said barrel with the storage receptacle, an auxiliary receptacle adapted to communicate with the 30 storage receptacle, a pressure conduit communicating with the auxiliary receptacle, a valve in each of said conduits, means for so connecting said valves that while one valve is opened the other valve is closed, means for 35 rotatably supporting the supply barrel, and means actuated by a rotation of the barrel for operating the valves.

Signed by me at Barmen, Germany, this 19th day of April 1910.

ROBERT HAUSDORF. [L. S.]
